UNITED STATES PATENT OFFICE.

OSCAR N. MORTENSEN, OF GRAND RAPIDS, WISCONSIN.

DENTAL FLUOROSCOPE.

Application filed March 15, 1920. Serial No. 365,745.

To all whom it may concern:

Be it known that I, OSCAR N. MORTENSEN, a citizen of the United States, and resident of Grand Rapids, in the county of Wood and 5 State of Wisconsin, have invented certain new and useful Improvements in Dental Fluoroscopes; and I do hereby declare that the following is a full, clear, and exact description thereof.

10 My invention pertains to new and useful improvements in fluoroscopes and has particular reference to such a device for dental use.

At the present time dental surgeons make 15 considerable use of the Röntgen rays in making photographs of teeth and the insides of patients' mouths so as to better enable them to make the necessary treatment. In making such photographs, however, it is necessary to wait until the negative has been developed before the part photographed can be examined, and this may take several days. Therefore I have adopted a fluoroscopic screen for use in connection with an X-ray 25 machine so that the inside of teeth or other members within the oral cavity may be examined without the necessity of making photographs.

As a result a dentist may readily examine 30 the progress of his work at any time and thus perform a certain operation much more effectively than is possible if he does not have this aid or if he has to wait until X-ray photographs have been prepared. The other advantages of examining parts of the human 35 mouth with the aid of Röntgen rays without making photographs are numerous and obvious.

Another object of the invention is to provide 40 a simply constructed fluoroscope for dental use which may be constructed in such a manner as to permit ready and effective sterilization.

With these general objects and advantages 45 in view the invention resides in the novel features of construction, combination and arrangement of parts which will be herein-after more particularly described and claimed and shown in the accompanying drawing, wherein:

Figure 1 represents a side elevational view, 50 partly in section, of a fluoroscope constructed in accordance with my invention.

Figure 2 is a detail transverse section 55 taken on the plane of the line 2—2 of Figure 1, and

Figure 3 is a view similar to Figure 1 of a slightly modified type of the invention, this being capable of use in a smaller mouth than the first mentioned form. 60

Referring more particularly to the accompanying drawing, especially to Figures 1 and 2, it will be seen that my invention consists of a cylindrical tubular casing 1 having one end flared outward as at 2 to provide 65 an eye piece, whereas the opposite end is turned laterally as at 3. The axis of the main portion of the casing is substantially at right angles to that of the laterally extending portion 3. These two parts may be 70 secured together in any preferred manner and at their intersection is located a fluoroscopic screen 4, the same being positioned at an angle of 45° to either of said axes. The open end of the laterally extending portion 75 3 may be closed by a suitable cap 5 when necessary.

The other form of the invention shown in Figure 3 also includes a cylindrical tubular casing 6 having an eye piece 7 at one end, its 80 opposite end being closed by a wall 8, the angle of which is 45° to the longitudinal axis of the article. The portion of the wall of the casing 6 adjacent the end wall 8 is provided with a substantially circular opening 9 for the reception of a fluoroscopic screen 10, and surrounding this opening is a cap receiving flange 11 on which a cap 12 may be placed. The inner surface of the end walls 8 is provided with a mirror 13 for reflecting the images visible on the fluoroscopic 85 screen 10 into and longitudinally of the casing 6. 90

The form of the invention illustrated in Figure 1 may be termed a direct type of 95 fluoroscope, whereas the other form is an indirect type in view of the reflecting mirror 13. With the parts arranged as in the indirect type, the fluoroscope may be made somewhat smaller for use in a patient's 100 mouth of smaller size.

In either case, however, the articles may be used in the same manner, the ends of the casings which house the fluoroscopic screen being inserted in a patient's mouth, whereby with the aid of rays from an X-ray machine, the insides of teeth and other parts are readily visible to the eye of the dentist at the opposite end of the casing. From this it will be seen that either type of the device may 110 be as readily placed in a patient's mouth as any other dental instrument. In view of

the fact that devices of this character are preferably constructed of metal, they are readily sterilized.

In addition to the changes illustrated in 5 the accompanying drawing, various others may be made to accommodate the invention to different uses, without departing from the principles thereof or sacrificing any of the obvious advantages.

10 I claim:

1. A fluoroscope for dental use comprising an elongated cylindrical metal casing for a very short distance having a sloping flange encircling one end, the other end having a 15 portion extending at right angles to the main axis of the casing and adapted to be inserted in a patient's mouth, a fluoroscopic screen disposed across the elbow formed by the two portions of the casing and forming 20 equal angles with the axes of the two portions, whereby the shadow formed by the X-rays on the screen will present the same appearance as if viewed through a direct

fluoroscope on a screen at right angles to its axis.

2. A fluoroscope for dental use comprising an elongated cylindrical metal casing for a very short distance having a sloping flange encircling one end, the other end having a 30 portion extending at right angles to the main axis of the casing and adapted to be inserted in a patient's mouth, a removable cap adapted to close the outer end of said right angle portion, a fluoroscopic screen disposed across the elbow formed by the two portions of the 35 casing and forming equal angles with the axis of the two portions, whereby the shadow formed by the X-rays on the screen will present the same appearance as if viewed through a direct fluoroscope on a screen at 40 right angles to its axis.

In testimony that I claim the foregoing I have hereunto set my hand at Grand Rapids, in the county of Wood, and State of Wisconsin.

OSCAR N. MORTENSEN.
